UNITED STATES PATENT OFFICE

GEORGE W. MULLER, OF WASHINGTON, DISTRICT OF COLUMBIA, ASSIGNOR TO MULLER RAILWAY TRACK SYSTEMS, INCORPORATED, OF WILMINGTON, DELAWARE, A CORPORATION OF DELAWARE

RAILROAD-TRACK STRUCTURE

Application filed June 16, 1928. Serial No. 285,852.

This invention relates to railroad track structure, one object being to construct the same in accordance with the most modern design, taking into consideration the fact that practically all roads have many wooden ties now on hand, as well as concrete or metal ties being tested out for future use. It is also an object of this invention to produce an improved track structure in which all or the greater portion of the materials at present available may be used.

For the past eighty years it has been the study and problem of railway constructing engineers and others, to devise the proper design and construction of railroad tracks at minimum cost. It is believed that this invention accomplishes that purpose, by reason of the showing in actual practical tests made on one of the most prominent railroads of this country for more than six months. Upwards of nine thousand trains, the equivalent of eight million wheel tons have passed over a section of track constructed in accordance with this invention, and no maintenance work whatsoever has been done to this section. This entirely satisfactory service in actual practice has resulted in the receipt by applicant of orders for further road construction on this line of railroad.

In order to more fully bring to light the principal objects of this invention, it is first necessary to call attention to the relatively weak points or features of the present day railroad tracks. Rails now used, regardless of their size or weight, have produced in them a wave motion. This motion is one of the leading causes of loosening the rail fastening devices and ultimately and inevitably bringing about the disarrangement of the track structure, because the wave motion sets upon a lever action or lifting effect from one tie across to the other and finally raises and dislodges the track spikes. It is an object of this invention to avoid this particular injurious difficulty entirely. Again, the wave motion makes the tie plates rock on the ties and cut pockets or depressions in the top of the tie, which lets the water enter under the tie plate, and this moisture subsequently rusts the tie plate and rots the tie, materially shortening the life

of both the tie plate and tie. Furthermore, the recurring wave motion in the rails due to the wheel loads passing over them, and the accompanying lever action as stated from one tie to another, pulls the spikes, and after the spikes are lifted from the tie the rails flap up and down constantly on top of the tie plates. This displacement tends to wear and beat down the plates into the ties, which very much lessens the useful life of the tie. It is believed that the use of this invention substantially eliminates this well known difficulty. Also, the wave motion established in the rails by the passing wheel loads, and the stated lever action incident thereto, in addition to loosening the spikes permits the lateral stress or side thrust of the wheels to push or knock the rails out of gauge sidewise, and this creates a corresponding lateral motion of the tie plates, which lets additional water down into the spike holes and under the tie plates and the ties rot and the plates rust more quickly. It is also true that the wave motion and lever effect from one cross tie to another under the repeated wheel loads, together with the hitting down on the rail joint beats the joint downwardly and outwardly and loosens bar plates and bolts. When the spikes are lifted and the rails become loose above the tie plates and ties, abrasion in or wear upon the bar joint and under side of the rail becomes so great that the heads of the bolts work into the side of the bar, or the bolts elongate in addition to the wear of the bar, and the rail becomes loose. This is a great drain upon the cost of maintenance and upkeep, and is really the beginning of the present track destruction. Oftentimes, the stated wave motion and lever action after lifting the spikes and loosening the rails above the tops of the tie plates and ties, on account of the present type of rolled joint bars, most of them with reinforced heavy and wide head projections when applied to the rail joints, cause the rail ends to become battered by the wheels hitting the projections, and the rails are sometimes split or chipped at the ends or break at the joints. The main reason for this trouble is the manner in which the bar fits under the rail head. When first applied it

gives a solid bearing under the rail head at the joint, and the small width of the bearing at the top of the bar plate and under the rail head causes the rail to cut down very quickly at the end into the bar plate. This distortion is multiplied or aggravated so quickly from the passing wheel loads that it is only a very short time until the rail ends are beaten down, which gives the wheel a greater opportunity for battering the head and thereby loosening the bars. This trouble occurs in spite of the practice of continually tightening the bolts along the many hundreds of miles of track. Another trouble with the joint bar at present in use is in being rolled of the particular design comprising a straight piece, and being of the same thickness from one end to the other. This construction results in dead pieces of material with no flexibility or having any spring action or tension in the way they fit the rail. The rail being also a dead piece of metal with no spring action, and the two or more dead pieces being bolted together in the manner in which they are commonly connected, the wave motion and lever action set up by the wheel loads passing over them soon causes them to wear or the bolts to elongate as described, and the bars drop down and the joint of the rails becomes impaired. It may be also stated that the wave movement and lever effect impressed upon the rails by the passing wheels, and the failure of the spikes to firmly secure the rails, impel the rails to push the ties from their beds, or makes them "creep," sometimes more on one side of the track than on the other side, and this distorts the entire track and gets it out of line and level, requiring the replacing of the ties in proper position, and tamping, driving in of the spikes, and tightening of bolts and other maintenance work all at added cost.

It is the purpose of this invention to avoid each and all of the objections referred to above in present railway track structure. The joint bar plates and associated devices made in accordance with this invention, are specially formed to hold the rail ends tight and up to a level line at all times, and they are so placed against the rails and bolted thereto and so fit the rails as to prevent the pumping of the joints, with the battering, splitting and chipping of the rail ends. Track structure fashioned in accordance with this invention always exerts tension at the rail joints both vertically and in a horizontal direction, the bolts being kept constantly under tension; therefore, as the wheel loads approach the joint the bar plate is ready to receive and adequately resist the blow or impact of the load. As the wheels bear the load over the joints from one rail to the next in line, the bar plates have a reflex action. The bar plate is so made that it holds the joint of the rails upwardly at all times, and when the bolts are inserted through the rails and near their ends,

the bolts are tightened because the ends of the bars are pulled in and upwardly on top of the rail flange or base, and the ends of the rails are lifted by the middle portions of the bars where they hug the web and under side of the ball or head of the rails near their ends. The vertical tension and reflex action of the bars is so exerted at the meeting line of the ends of the rails, that when the wheel passes over and hits the joint the bar has a springing back movement and fully recovers its normal position keeping the track always level.

It is impossible to hold a rail joint and bar plates of present day design always in place in railway tracks as they are now constructed, by driving a track spike down through a single tie plate into the wooden tie, or into a wooden plug and a concrete tie, or when bolts or clips are employed in connection with metal ties. The reason is the wave motion and lever spike-lifting action hereinabove explained. This applicant uses a longer tie plate or base plate under the rails on top of the ties, and such base plates may be screwed down to the ties through the outer edges, and the rails may be fastened to the tie plates in the spaces between the ties, thereby making a much more flexible track. The ties cannot then be pushed from their beds or creep, because the greater part of the effect of the wave motion in the rails will be eliminated, and inasmuch as the applicant uses no spikes in this form of railway track structure next to the rail to hold it down, the slight unavoidable wave movement is taken care of, as the tie plates have flexible vertical motion to go and come up and down with the rail, and the rail cannot be displaced.

The longer tie plate or base plate is very necessary to the improved track structure of applicant as disclosed in this description, for several reasons:—

A. It is desired to give the rail a bearing more uniformly upon a plurality of ties, which will distribute the weight of passing loads equally over the roadbed below the ties.

B. By forming screw holes through the plate on its outer edges, and to fasten the plate to the ties by screws, spikes or any equivalent holding means passed through those holes, confines a layer of air at atmospheric pressure between the bottom of the tie plate and the top of the tie, and this layer of air is in a measure compressed under the sudden impact of the wheel loads, and will not allow the plate to cut or beat down into the material of the tie but will give a rebounding and resilient bearing for the rail upon the ties. It may also be stated here that the plates being wide and long and covering over the full width of the top of the tie, will keep water from getting under the plate into the tie or holes therein.

C. An important object of forming the tie

plates in relatively long sections fastened to the ties through their outer edge portions, is to prevent the ties from creeping, slipping, or sliding and moving from their normal place in the roadbed.

5 D. Another object in forming the tie plates of long sections and securing them as described upon a number of succeeding ties, is to hold the edges of the rail base flanges in line, particularly at the joints, and to prevent them from being forced out laterally on one side, and from being pulled out of line on the other side of the track by the wheel thrust or blows sidewise against the joints.

10 E. Another object in employing longer tie plate members running across the tops of a plurality of cross ties, is to really aid in strengthening the rail against breaking should a defect exist in the rail.

15 F. Another object of the tie plates being fastened as set forth over a number of ties, is to hold the top face of all ties up to a like level horizontal line, in order that tamping can be done more easily and quickly under the bottoms of the ties when necessary.

20 G. Another object of the plates being made in long pieces and fastened to and upon the tops of a plurality of neighboring cross ties, is that they will seat themselves in a body, 30 that is to say, in numbers more uniformly and stay in place in the roadbed and hold the track level.

25 H. Another object of the tie plates where used in long sections or various lengths as desired, and opposite each other particularly where joints occur in the rails, is to afford a balanced track. That is to say, one side of the track cannot be displaced with respect to the other side.

30 I. Another object of the long plates covering a number of ties is to maintain the ends of all the ties in place at right angles to the plates, and to keep the ties from spreading fan-shaped on one side or the other. To hold the track and rails to gauge, particularly where the rails have a tendency to the displacement of the joints laterally, it is most essential that two tie plates be used on opposite sides in track structure according to this 45 invention, because the rails and tie sections must be held together so that they cannot creep or move.

40 J. An object of the over-lip tie plate is to hold the rail flange down to the tie plate 50 and to avoid the greater part of the wave motion and the injurious effects thereof. It is not necessary, however, to always have the over-lip plates, as the holding keys introduced by this applicant can be used on both 55 sides of the rail with either a plain plate or with a single lug or upstanding shoulder if desired.

55 Rail joint bars and bolts add about one hundred pounds more weight to the rails at their ends and at the joints, and the weight

acts as an aid in pushing down the joint. The tie plates covering the full width of the ties increase the square inches of wood bearing surface, and as the plates are fastened to the ties in longitudinal sections or continuously, the load is uniformly distributed as previously explained.

70 In this track structure the applicant has provided a rail and tie plate holding means comprising a clamp or key for holding the rail to the tie plate, and spike pins to be driven through the tie plate or through the top of the key and tie plate as may be preferred, and the bottom parts or legs of the spike pin spring open after driving them through the key and plate and holds the spike pin down and in place back against the clamp pin. The spike pin is made with a head like a track spike, in order that it may be lifted from the hole in the clamp or plate 75 with a short handled lifting spike pry lever. The clamp pin, or key and spike pin are made to drop through a hole in the tie plate away from the side edges of the ties, or through the tie plate where it crosses the 80 space between the ties, in order that they may act together to hold the rail to the tie plate with the rail pressure directly over and upon the tie, and there is no spike or key at the side of the rail to be drawn out or 85 loosened by the repeated wave motion and lever effect.

90 It is believed that by the use of this invention and the rail and tie plate holding means set forth, there is attained a great saving of labor, time and expense where new rails are to be laid in a track, or removed, or shifted, or changed from one size to another.

95 In this track structure application it will be noted that the accompanying drawings show one of the several rail joint bars invented and patented by this applicant, and while it is preferred to use one or the other of such joint bars which are specially effective for the purpose, any joint bar could be substituted. 100 But, it must be understood that this invention is held by the applicant to include the use of any form of joint bar. This application is for an improved track structure consisting of the several parts or members in combination, as hereinafter more fully described and illustrated in the accompanying drawings 105 forming a part of this application.

110 Figure 1 of the drawings represents a side view of a portion of a railway track constructed in accordance with this invention, and showing the joint of two rails, the joint bar applied thereto, with the relatively elongated tie plate upon a plurality of ties, and showing also the position of the holding spikes. Figure 1 is a side view from outside 115 the rails.

120 Figure 2 is an inside view of the track construction as set out in Figure 1, showing the 125

positions of the spike pins through the tie plates and between the ties.

Figure 3 is a top plan view of the parts set out in Figure 1 and Figure 2, and shows the positions of the bar plates and other parts on both sides of each rail.

Figure 4 is a side view of a portion of a railroad track structure made in accordance with this invention, and showing a shorter tie plate, with adjacent ties each having a single tie plate. The tie plate has a raised shoulder.

Figure 5 is a side view of a portion of a track structure as shown in Figure 4, the tie plate having an over-lip in engagement with the base flange of the rail, and showing the positions of the track or tie spikes.

Figure 6 is a side view of a portion of track structure, showing a tie plate resting at its ends on pairs of ties and showing the positions of the track spikes and the spike pins. This figure differs from Figure 4, in which figure the pair of ties is directly under the rail joint.

Figure 7 is a top view of the rail joint as illustrated in Figure 6.

Figure 8 is a side view of a rail, showing the rail joint supported by three grouped ties, and showing also the positions of the tie spikes and the spike pins.

Figure 9 is a top view of a rail and tie plate carried by the three grouped ties as set out in Figure 8.

Figure 10 is a side view of a rail joint, having parts similar in construction to those illustrated in Figure 5, the tie plate having an over-lip, but being shorter in length than the corresponding tie plate in Figure 5.

Figure 11 is a vertical section through a tie plate and transversely through the rail upon the plate, showing the portions of the bar plate spaced from the web of the rail. This section is taken through the bar plates about one-third of length from one end.

Figure 12 is a vertical cross section of a rail and tie plate, and is taken through the middle of the bar plates showing the hug of the web and the head of the rail.

Throughout the description and drawings, the same number is used to refer to the same part.

Considering Figure 1, the rails 1 and 2 are brought together as usual end to end, and they are joined by the bar plate 3. The bar plate has the heavy middle portion 4 outwardly and downwardly faced as shown in Figure 12, and the ends 5 and 6 of the bar plate are reduced somewhat for a distance from the extremities as shown. The middle bolts 7 and 8 compel the middle of the bar to hug the web and under side of the head of the rails, while the bolts 9 and 10 through the end portions 5 and 6 spring those portions towards the web. In other words the ends of the bar plate are elastic and their spring quality keeps the bolts 9

and 10 always under tension. In Figure 1 the positions of the tie spikes 11 are set out. Those spikes pass through suitable holes near the edges of the relatively long tie plate 12, and are driven well within the edges of the ties 13.

Considering Figure 2, the fellow bar joint plate 14 is shown on the inside of the rails, and in this figure the spike pins 15 and their positions are set out. It will be observed that the spike pins have substantially spike heads, and outwardly bowed spring legs. One of the spike pins in Figure 2 has the head marked 16, and the spring legs 17. As illustrated in Figure 2 and also in Figure 3, the spike pins are forced through suitable holes in the tie plates 12 between the ties and usually on the inside of the track as shown nearer to one tie than to the next tie.

In Figure 3 both bar joint plates 3 and 14 are shown connecting the ends of the rails.

Considering Figure 4, the rails 18 and 19 are held together by the bar plate 20 of the same construction as before, and arranged in the same way and help by bolts as previously stated. The tie plate 21 is shorter than the like plate in the former figures, and has a raised over-lip 22 engaging the flange of the rails. In this figure, the ends of the tie plate 21 are supported upon the ties 23 and 24, to which the plate is secured by the tie spikes 25. The middle portion of the tie plate 21 and the joint of the rails are directly carried upon a pair of ties 26 and 27 arranged near together. This arrangement may be varied as illustrated in Figure 5, in which the parts are the same as in Figure 4, but instead of placing a pair of ties immediately under the middle of the tie plate 27, a single tie is located directly below either end of the joint bar plate. Those ties are referred to by numbers 28 and 29. It will be noted that the tie plate 27 is somewhat longer than the tie plate 21 shown in Figure 4. The view set forth by Figure 5 is taken from the outside of the joint of the rails, and the positions of the tie spikes are shown.

Considering the further modification shown in Figure 6, the rails 30 and 31 are joined by the bar plate 32, and rest upon the tie plate 33. This figure represents an inside view of the rail joint, and the ends of the tie plate are carried by pairs of ties, 34 and 35 composing one pair, and ties 36 and 37 the other pair. In this figure will be noted the spike pins, which are of exactly the same construction as those described in connection with Figure 3 hereinabove. The spike pins are shown passed downwardly between the members of the pairs of closely associated ties supporting the ends of the tie plate 33, and they are also located between or in the space separating the pairs of ties.

Figure 7 is a top view of the same parts as those comprising Figure 6, and the fellow

to bar plate 32, marked 38 is shown on the outside of the rails.

Figure 8 represents still another arrangement of this invention. This is also an inside view, meaning a view taken of the meeting ends of the rails from between the rails. The rails 39 and 40 are connected by the bar joint plate 41, which is the same in form as before. The tie plate in this figure is but little longer than the bar plate and is marked 42. Supporting the plate directly are three ties 43, 44 and 45, arranged closely together, and it will be noted that the spike pins are located in the spaces between the ties after 15 passing downwardly through the tie plate as illustrated.

Figure 9 is a top view of the same parts as those comprising Figure 8, and the fellow bar plate 46 to the bar plate 41 is shown in position connecting the rail joint.

In the arrangement of this invention as shown in Figure 10, the rails 47 and 48 are connected by the bar plate 49 which is of the same form as before. The tie plate 50 has 25 the over-lip or raised shoulder 51. This figure is an outside view of the rails, and the track spikes are shown in place. The tie plate 50 has its ends directly supported by the ties 52 and 53, and between them and immediately 30 beneath the rail joint is a third tie-plate-supporting tie 54. All the ties are regularly spaced apart in Figure 10.

The parts of this railroad track structure illustrated in Figure 11 are the tie 55, the tie plate 56 having the over-lip 57 engaging the flange 58 of the rail 59. The tie spikes 60 pass through the tie plate near its edge as stated and into the tie. The clamp key is marked 61 and the clamp pin securing the 40 key to the flange 58 and to the tie plate is designated by number 62. Those parts are formed, arranged and coact as set forth in prior patents of the United States in my name, and call for no individual description 45 at this time. Above the flange and spaced from the sides of the web of the rail are shown sectionally the ends 63 and 64 of bar joint plates having the form already described. A bolt 65 passing through those ends and 50 through the web of the rail is plainly always under tension, and cannot be jolted or knocked loose in any way. It will be borne in mind according to this specification that the ends of the bar joint plates are resilient both horizontally and vertically. Therefore, the middle and heavier portions marked 66 and 67 in Figure 12 are constantly pressed up upon the slanting top of the flanges of the rails and caused to hug the web and head of the 55 rails tightly at all times.

In making a statement of the operation of this invention, attention is requested to the fact that each of the modifications illustrated in the drawings and described in the 65 foregoing explanation, consists of the same

parts as each of the others and those parts are of substantially like construction and purport. In every instance there is found the tie plate extending over a plurality of neighboring ties, the plates being spiked to the ties by spikes through the edges of the plates. The rails are secured to the tie plates by spike pins located between the ties, and the rails themselves are held end to end by bar joint plates on opposite sides of the joint, 70 those plates being bolted together through the rail web, and possessing a powerful elastic quality horizontally as well as vertically. It is the combination of all these special members as set forth that enables the applicant to successfully overcome every one of the objections to the present day structural practice as stated in detail at the beginning of this specification.

Having now described this invention and 85 explained the mode of its operation, I claim:—

1. A railroad track construction, comprising a succession of cross ties, tie plates each resting upon a segregated group of the ties, rails meeting upon the tie plates, rail joint bars adapted to connect the ends of the rails independently of the plates, and means for securing the rails upon the tie plates between the ties.

2. In a railroad track structure, the means for reducing wave motion and lever action in the rails, comprising track cross ties, relatively elongated tie plates each covering a segregated group of the said ties transversely, 90 means for securing the plates upon the ties, rails having their ends meeting at substantially the middle of the length of the said plates, means located between the said ties for securing the rails upon the said plates, 100 and means secured to the said rails only for connecting the ends of the rails.

3. A railroad track construction, comprising a succession of cross ties, relatively elongated tie plates each secured upon a plurality of the said ties, means for securing the plates to the ties, means for securing the plates and rails together, joint bars having vertically resilient end portions bearing 110 on the rail bases secured to the rails under tension horizontally, the said bars having solid middle portions fitting the webs and heads of the rails, whereby approaching wheel loads raise said middle bar portions.

4. In railroad track structure, the means for reducing wave motion and lever action in the rails, comprising cross ties, relatively elongated tie plates each covering a plurality of the said ties transversely, means for securing the plates upon the ties, rails having their ends meeting upon the said plates, and joint bars secured to the rails and having vertically resilient end portions bearing on the rail bases whereby approaching wheel 120

loads raise the middle of each bar against the under side of the head of the rails.

5. A railroad track structure, comprising a series of ties, tie plates each adapted to extend over a plurality of ties, the ends of the said tie plates being directly supported by members of segregated groups of ties arranged beneath the said plates, rails meeting upon the plates, bar plates connecting the ends of the rails upon and of less length than the plates, and the joints of the rails being arranged directly above members of the said groups of ties supporting the tie plates.

15. A railroad track structure, comprising a series of ties, tie plates each adapted to extend over a plurality of ties, rails meeting upon the said plates, bar plates arranged to connect the ends of the rails upon and of less length than the plates, and segregated 20 groups of closely associated ties located directly below the said bar plates and under the tie plates to support the tie plates.

25. A railroad track structure, comprising a series of ties, tie plates each adapted to extend over a plurality of ties, rails meeting upon the said tie plates, bar plates connecting the ends of the rails upon and of less length than the tie plates, means for securing the tie plates to the ties, a plurality of the 30 said ties being arranged in segregated groups beneath the said tie plates and bar plates, and means for securing the rails upon the tie plates and arranged to pass between the said ties lying beneath the plates.

35. A railroad track structure, comprising a series of ties, tie plates each adapted to extend over a plurality of ties, rails meeting upon the tie plates, bar plates arranged to connect the ends of the rails upon the tie plates and having end portions resilient vertically and horizontally, and segregated 40 groups of ties closely associated and arranged below the said bar plates and under the tie plates, the said rails being provided 45 with means for securing them to the said tie plates and arranged adjacent to the bar plates.

In testimony whereof I affix my signature.
GEORGE W. MULLER.
